MOTOR

James J. Gough, Chicago, Ill., assignor to Chicago Electric Manufacturing Company, Chicago, Ill., a corporation of Illinois

Application July 29, 1940, Serial No. 348,268

13 Claims. (Cl. 172—36)

The present invention relates to a household or culinary appliance and more particularly to a combined mixer and juicer.

The invention yet more specifically contemplates an appliance of the foregoing class comprising an electrical drive motor and adjustably associated with a supporting member so as to be readily shiftable into a position wherein the motor is operable to beat, whip or mix fluid materials, or in another position to receive a suitable juicing reamer for abstracting fluid juices from fruits and vegetables.

It is an object of the present invention to provide an appliance of the foregoing class wherein the drive motor housing presents an outwardly extending drive shaft on one side only thereof and wherein the housing is associated with its support in either of the plurality of operative positions so that the shaft is presented in proper position for the particular operation desired, a rigid and stable support being effected in any operable position.

Yet more particularly, it is within the contemplation of the present invention to provide a combined mixer and juicer as above in which the motor unit is selectively removable or releasable from a supporting pedestal and adapted to be interlocked therewith in any of the plurality of foregoing positions.

It is a further object of the present invention to provide a combined mixer and juicer construction as above wherein the driving and mixing assembly, while in mixing position, is selectively shiftable to a position remote from the mixing zone for removal or observation of the material under treatment.

A further object of the present invention contemplates the provision of an improved drive motor housing comprising a clamping band separably interengaged by housing supporting brackets whereby the operative association of the brackets permanently holds the entire housing in assembled relationship.

Another important object of the present invention comprises the provision of improved adjustable limiting stop mechanism positively and adjustably locating the whipping mechanism with respect to the whipping bowl.

Other and further objects of the present invention are to provide an improved ventilating system operable to direct all of the air agitated by a fan directly upon and through the interstices of the drive motor; to provide an improved positive interengagement of the drive motor assembly with the supporting base in juicing posi-

tion; and to provide a compact, simplified mixer and juicer of improved appearance, occupying a small space for storage, and portable in character.

5 Yet other and further objects will be apparent from a consideration of the following specification and drawings, wherein:

Figure 1 is an elevational view of a device constructed in accordance with the present invention and arranged in position for beating or mixing the contents of the bowl;

Figure 2 is a front elevational view of the construction of Figure 1;

Figure 3 is a detailed sectional view taken centrally through the upper portion of the supporting pedestal and associated bracket portions of the motor housing;

Figure 4 is a detailed sectional view taken through the detail of Figure 3 on the line 4—4 thereof;

Figure 5 is a detailed elevational view substantially the same as Figure 1 and showing the drive housing swung away from beating or mixing position;

Figure 6 is a detailed sectional view taken on the same plane as Figure 3 and indicating the relative positions of the parts when located in the relative arcuate position of Figure 5;

Figure 7 is a detailed sectional view taken centrally through the motor housing on the line 7—7 of Figure 1;

Figure 8 is a detailed sectional view taken on the line 8—8 of Figure 7;

Figure 9 is a sectional view taken across the motor housing of Figure 7 on the line 9—9 thereof;

Figure 10 is a perspective view of one of the motor housing brackets;

Figure 11 is a perspective view of the ventilating air directing shroud shown in Figure 7;

Figure 12 is an elevational view of the parts relatively arranged for carrying out a juicing operation;

Figure 13 is a plan view of the reamer and juice receptacle shown in Figure 12;

Figure 14 is a detailed sectional view taken through the device on the lines 14—14 of Figures 12 and 15;

Figure 15 is a sectional view taken horizontally through the gear housing of Figure 14 on the line 15—15 thereof;

Figure 16 is a perspective view of the locking clamp for interengaging the driving mechanism with the supporting pedestal in juicing position;

55 Figure 17 is a detailed perspective view of the

end extremities of the motor housing brackets; and

Figure 18 is a detailed sectional view showing the interlocking engagement of the supporting base with the apex of the motor housing.

Referring now more particularly to the figures of the drawings, wherein there is disclosed one illustrative embodiment exemplifying the principles of the present invention, Figures 1 and 2 disclose a juicing and whipping appliance comprising a drive assembly 10 and a supporting base construction 12. It will be seen that the drive motor assembly comprises a motor housing 14 containing a suitable driving motor and a permanently associated rigid supporting bracket assembly 16. From the lower portion of the housing, projects a pair of drive shafts 18 interengageable with whipping agitators 19 which may extend into a bowl represented by the dotted lines in Figures 1 and 2.

The driving assembly, as shown more clearly in Figures 1, 2, 7 and 9, comprises a housing having an upper dome-shaped shell 20 and a lower concave section 22 provided with annular side walls and outwardly flanged as at 24, providing axially facing recesses to receive opposite corner margins of the laminated core 26 of the electric drive motor 28. In order to hold the upper and lower shells 20 and 22 axially upon the laminated core 26 in the position shown in Figure 7, there is provided an annular clamping band 30 extending about the angular flanges 24 as shown in the figure, and having radially extending marginal peripheral flanges 32 oppositely embracing the complementary radially extending portions of the flanges 24. The flanges 32, being disposed outwardly of the flanges 24, oppositely embrace the latter, permanently completing the housing assembly.

From the foregoing, it will be apparent that the band 30 embraces the shells in the position shown, terminating in opposed circumferential extremities 34 projecting radially outwardly in spaced parallel relationship as indicated by the dotted lines in Figure 1.

Attention is directed to the fact that the projecting lugs or extremities 34 are restrained by a pair of complementary brackets 36 configurated as shown in Figure 10 and having permanent interlocking engagement with the housing. To this end, each of the brackets comprises a side wall 38 narrowed at its central portion and cut away or relieved as at 40 (see Figure 10) in a recess complementary in form to the clamping band 30. As clearly shown in Figure 1, the recess 40 permits the extremity of each bracket to reside against the circumferential wall of the motor housing with upper and lower margins 42 in juxtaposition to the upper and lower housing shells 20 and 22, respectively. Particular attention is directed to the fact that the margins 42 are each provided with a lug 44 projecting a short distance in the plane of the bracket as at 46 and then bent laterally as clearly shown in Figure 10. It will be appreciated that each tab or lug 44 is received in a complementary aperture or slot (not shown in detail) in one of the shells 20 or 22 so that each pair of brackets 36 may merely be clipped into the housing, as shown in Figure 1, after the clamping band is in position and when so arranged will bear a rigid, fixed angular relation to the housing, adapted to resist any substantial distortion.

It will be apparent from the foregoing that with a pair of complementary brackets 36 engag-

ing the housing on opposite sides of the clamping band extremities, the latter are permanently retained in the position shown. The brackets are permanently held in the position shown to tension the extremities of the clamping band by a clamping screw 48 projecting therethrough at aperture 50 and through the lugs 34.

It is though that important simplification of assembly operations will be apparent to those skilled in the art from a careful consideration of the foregoing. Thus, after merely locating the housing shells and clamping band in the position shown, the complementary pair of brackets 36 are shifted and interlocked with the housing by shifting the lugs 44 through the complementary apertures or slots and applying tensioning member 48. It will be appreciated that the recesses or housing slots to receive the lug portions 46 may preferably be somewhat circumferentially elongated within minor limits to facilitate appreciable application of tension through the agency of the clamping fastener 48. It is obvious from the foregoing that the present construction eliminates the prior costly and protracted assembly process involving welding and at the same time positively interlocks the bracket and the housing against displacement in any relative direction. It will be appreciated that this is of material importance where the weight of the driving assembly must be supported in fixed angular relationship while under appreciable load.

As further shown in Figure 10, each of the brackets 36 is provided with an inwardly projecting rigidifying flange 52 limiting the approach of the opposed complementary brackets in assembled relation. The opposite or right hand extremity of each of the brackets 36, as viewed in Figure 10, is flared in its plane to provide an upper or handle engaging section 54 apertured as at 56 to receive a handle attachment pin or fastener 58. The handle portion of the driving assembly comprises a manually engageable handle bracket 60 conveniently shaped for manual engagement at its central portion and having its lower extremity extending between the opposed sheet brackets 36 as shown in Figures 1, 3, 4, 5 and 6. As clearly shown in these figures, the illustrated fastener 58 comprises a pin and bolt applying a permanent clamping force to rigidly clamp the handle bracket 60 between flange portions 54.

The upper portion of the handle bracket 60 has a surface 62 complementarily engaging the dome of the upper surface of the housing shell 20 and fastened by a filister headed fastener 64. As clearly shown in Figure 7, the fastener engages the housing at 66 and a washer 68 below the head of the fastener permits the latter to provide a cylindrical interlocking projection for a purpose which will hereinafter appear more in detail. From the foregoing it will be obvious that the handle bracket 60 has rigid permanent engagement with the motor housing and the sheet brackets 36 provide a rigid unitary assembly.

Referring more in detail to Figures 7 and 8, it will be seen that the motor 28 is of conventional form disposed centrally and axially of the housing with the drive shaft extending downwardly and bearing at its lower extremity a pinion 70. Pinion 70 interengages both of a pair of gears 72 fixed to the upper extremities of the shafts 18. The gears 70 and 72 are disposed within a gear transmission housing 74

having a cover 16 held in position on the housing by fasteners 78 which also extend through the lower wall of the housing shell 22 for locating the transmission housing 74 within the shell. Projecting sleeves or bushings 80 on the transmission housing extend downwardly about journal portions in the shafts 18 and oil sealing collars 82 on the shafts 18 bear against the lower faces of the bushings 80 to prevent leakage of lubricant from the transmission housing.

The beater or whipper units 19 couple releasably with the lower extremities of the shafts 18 by virtue of suitable coupling means shown in Figures 1, 2 and 7 comprising a sleeve 84 rigid with the upper extremity of each beater for embracing the lower end of a stub shaft 18. Each of these shafts is complementarily relieved on opposite sides of a central axial plane, as clearly shown in Figure 7, for rotational interengagement. In other words, each of the shafts is provided with complementary radial abutment faces for transmitting rotational movement. It should be noted that the beater shaft has a beveled portion 86 to facilitate entry of the stub shaft 18 into the recess formed by the cut away portion. A resilient spring arm 88 fixed to the lower extremity of sleeve 84 extends thereabove and is apertured to embrace the shaft 18. By virtue of being tensioned in a lateral direction, the shaft embracing portion accordingly tends to interengage in an annular groove 80 in the shaft 18. Accordingly, in the position shown, each beater is axially latched to the shaft while being interlocked against relative rotation and may be readily released by manually shifting the spring latch 88 until its aperture aligns coaxially with shaft 18, when the parts may be axially separated.

Provision is made for efficiently ventilating the drive motor by means of a fan impeller 92 mounted upon the upper projecting portion of the motor drive shaft. The fan is configurated to direct air downwardly wherefore apertures 94 in the upper shell 20 supply a current of air passing downwardly about the motor and exhausting through lower elongated slots or apertures 96. I have particularly noted that in many of the conventional constructions with which I am familiar, the aero-dynamic design is such that the cooling impeller permits the air to circulate inefficiently about housing portions requiring no cooling. In other words, there is frequently a tendency to induce circulation at points remote from the heated portions of the motor, resulting in ineffectiveness of the cooling system and loss of power. The present invention contemplates the propulsion of all of the cooling air directly against and through the motor. In short, the present construction concentrates the direction of the cooling air to the motor parts which require cooling. To this end, there is provided an inner shell or shroud 98, shown in Figures 7, 9 and 11, having annular conical side wall 100 terminating at its lower extremity in an annular shell engaging flange 102 and at its upper extremity in a radially extending flange 104. This cowling or shroud is snugly received within the lower portion of the dome-shaped shell 20 and embraces the marginal periphery of the fan impeller 92. It will be obvious from the foregoing that the shroud necessitates axially downward flow of all air handled by the fan blade 92 and directs the air axially upon and through the interstices of the motor. While I have provided an aperture 106 for passage of an electrical sup-

ply conduit 108, it will be understood that the aperture is relatively restricted and is occupied by the conduit 108 whereby air leakage is prevented. It will be apparent, moreover, from the foregoing that the present construction necessitates axial flow and inhibits all tendency for the impeller blade to set up radial and peripheral flow of air, whereby the blade efficiently directs all of the air passing successively through apertures 94 and 96 directly against the parts to be cooled. A snap switch 109 is mounted on the upper portion of the housing in convenient location for controlling actuation of the motor.

Referring now to the supporting construction 12, this comprises a flat base portion 110 from one side of which extends an upwardly projecting pedestal 112 engageable with the motive drive unit as shown in Figures 1 and 3 to 6. As clearly shown in these figures, this letter means comprises a pin 113 permanently horizontally mounted in the upper extremity of the pedestal and having journal portions 114 extending laterally on either side of the pedestal and terminating in headed abutments 116. The journal portions 114 are adapted to be received in T-shaped slots 118 in the plate brackets 38 which laterally embrace the upper extremity of the pedestal 112 on either side thereof. This pin and bracket interengagement provides a fulcrum about which the driving unit is adapted to swing between the position shown in Figure 1 and that illustrated in Figure 5. These two positions permit the fixture to be arranged selectively within a mixing bowl as shown in Figure 1, or in a relatively remote and elevated position to permit removal of the bowl.

The present invention provides for adjustment of the lowermost position by means of a stop abutment shown more clearly in Figures 3 and 6 and comprising a bar 120 extending between the two bracket members 36 and welded or otherwise fastened rigidly in position in the apertures 122 (see Figure 10), preferably with the extremities of the bar extending laterally outwardly beyond the plates 36 a short distance in view of an object which will hereinafter appear more in detail. It will be noted that the bar 120 is relatively close to the fulcrum pin 113 on the pedestal and the upper end of the pedestal is accordingly cut away as at 124 to permit rotational swinging of the bar 120 with the remainder of the motor unit. In the lowered position of the motive drive unit, the bar 120 rests against an inclined face 126 of adjustable abutment member 128 shiftable vertically in a complementary recess 130 provided in the pedestal 112. The abutment bar or shaft 120 is notched as at 132 with a laterally outwardly facing V-shaped groove or notch extending in a direction normal to the axis of the abutment shaft 128 and providing upper and lower inclined surfaces in planes inclined with respect to said axis. Attention is particularly directed to the fact that this notch is normally engaged by the conical extremity 134 of a set screw 136 extending horizontally through the upper portion of the pedestal 112 and threadedly engaged therewith. Since the inclination of the conical surface 134, where it engages the pin 128, is complementary to the inclination of the adjacent pin surface, it will be seen that the bounding planes of the notch 132 and the conical planar surface 134 form cooperating cam portions which coact to control the elevation of the inclined abutment surface 126. In other words, as the adjustment screw 136 is threadedly shifted inwardly of the

pedestal, the conical surface 134 rides along the upper surface of the notch 132 to urge the abutment upwardly. When the set screw is shifted to the right, as viewed in Figure 3, the pin 128 is permitted to drop a corresponding distance, accordingly lowering the pedestals 19 with respect to the mixing bowl. With the motive drive unit in angularly remote position, it should be noted that the bar 120 resides against a vertical abutment face 138 defining one extremity of the cut away or relieved portion 124 of the pedestal. Particular attention is directed to the fact that in moving angularly with respect to the fulcrum pin 113, the T-shaped slot 118 shifts slightly with respect to the fulcrum pin 113 to vary the relative location thereof.

It will be obvious from the foregoing that this minor shifting of the fulcrum permits an additional movement of the motor housing sufficient to locate the center of gravity beyond the right hand side of a vertical plane passing through the pin 113 and as viewed in Figures 1 and 5. In other words, the coaction of the fixed fulcrum pin 113 and the relatively elongated slot embracing the pin enables the disposition of the motor housing under stable conditions in the angularly remote position and without necessitating any undesirable degree of angular movement. That is to say, the present construction contemplates the coincidental shifting of the driving member and its fulcrum point in opposite angular direction whereby they cooperate to shorten the total movement necessary to bring the member into a position of equilibrium.

While the foregoing description concerns the arrangement of the drive unit in one cooperative relationship with the supporting means and particularly suitable for mixing and whipping, the invention comprehends the fixed disposition of the same unit in a substantially reversed position as indicated in Figures 12 to 18 whereby to facilitate juicing and similar operations. It will be appreciated from the foregoing that by virtue of the T-shaped slot constructions 118 in the pedestal engaging bracket, the driving unit is freely removable from the pedestal and when inverted in the position shown in Figure 12 is adapted to receive a transmission housing 142, together with a juicing reamer 144 and a juice trough 146. Attention is particularly directed to Figures 12 and 18 indicating the manner in which the projecting lug formed by the flister headed fastener 64 is received within a complementary recess 148 in the base 110 of the supporting unit 12. It will be seen that this inter-engagement fixedly locates the driving unit in the plane of the base portion 110. Fixed engagement against relative vertical and angular movement is provided by means of a locking clip or bracket 150 shown more in detail in Figures 12 and 16. The bracket 150 includes a pair of parallel side portions 152 joined by a top web portion 154 and having laterally aligned slots 156 to embrace the laterally projecting pin portions 114 of the pedestal. A pair of aligned apertures 158 receive a cooperating threaded fastener and wing nut 160, operative to yieldably tension the side walls 152 grippingly against the side face of the pedestal 112 when disposed thereover as shown in Figure 12.

Attention is particularly directed to the configuration of the opposite or left hand extremities of the side webs 152 as viewed in the figures, comprising a shouldered portion embodying a horizontal surface 162 and an angularly disposed

downwardly extending surface 164. Stated in other words, these two surfaces cooperate to provide complementary recesses for receiving the laterally extending extremities of the pin or bar 120, which extremities have been designated in Figures 12 and 17 by the reference numeral 166. When received by the locking clip as shown in Figure 12, the motor drive unit is effectively restrained from vertical and rearward movement by the abutments 162 and 164. Similarly, all tendency for rotational movement with respect to the point of engagement with the base 110, and as indicated by the arrows in Figure 12, is likewise resisted. Since the bracket plates 36 are embraced between the side flanges 152 of the clip, it will be seen that the unit is held against lateral movement.

From the foregoing, it will be apparent that the present construction provides a very simple and effective means for rigidly locating the motive unit in the position shown.

There is disclosed in Figures 14 and 15 the general construction of the transmission unit 142, including an outer cylindrical casing 168 having a lower annular flange 170 adapted to embrace a portion of the motor housing shell 22. A central transverse partition 172 within the housing 168 mounts a pair of vertically extending sleeves 174 for receiving the stub extremities of the drive shafts 18 while the partition 172 rests upon the shaft collars 82. It should be particularly noted that one of the shafts only engages with one gear of a reduction gear train indicated in general by the reference numeral 176 disposed within a cage 35 comprising the partition 172 and an upper partition 178 joined by a plurality of fixed spacer bars 180. The final gear 182 of the gear train is rigid with a reamer shaft 184 projecting upwardly through a sleeve 186 secured to the upper partition member 178. Accordingly, it will be seen that the entire transmission assembly including the reamer shaft, journal and sleeve comprises a unit axially disposable within the cylindrical housing 168 and held therein by a plurality of 45 flat headed machine screws 188. Thus, it will be apparent that the fasteners 188 extend through the upper wall of the housing 168 to engage the upper partition 178 of the transmission unit. As clearly shown in the figures, the non-circular 50 extremity of one of the drive shafts 18 engages the initial pinion of the gear train, whereby the reamer shaft 184 is rotated at a relatively reduced predetermined speed when the motor is actuated. The other shaft 18 rotates idly.

55 The upper surface of the transmission 142 supports the more or less conventional juice receiving trough 146 containing a strainer 190, and the reamer 144 separably rotates with the shaft 184 by means of a polygonal coupling sleeve 192 fixed to said shaft and received by a complementary recess in the reamer.

From the foregoing, it will be apparent that in use the present device may be employed either as a whipper or juicer, with the drive shaft means 65 projecting either vertically downwardly or upwardly as desired. In the former arrangement, the T-shaped slot 118 of the supporting bracket is merely disposed over the laterally extending fulcrum pin 113 of the pedestal when the entire drive unit may be swung about the pivot. The operator has at his disposal the adjustment screw 136 operable to positively determine the elevation 70 of the whippers or beaters with respect to the bowl, while being enabled to accurately move the

entire beating assembly out of the bowl to a remote position of positive stability.

Transition to a form suitable for juicing is effected simply by removing the driving assembly from the supporting means and inverting it upon the supporting base with a drive shaft extending upwardly, in which position the holding clip 150 is applied to clampingly grip the pedestal and the drive unit bracket. The transmission housing and reamer are freely disposed over the projecting drive shafts to positively connect the reamer in driving relation to one of the shafts. It is evident that in either position of use, the parts are rigidly interlocked and held by the supporting member and thus fixedly located with respect to the supporting surface.

From the foregoing, it will be evident that the present invention simplifies the construction of appliances of the present class by eliminating the plurality of drive connections conventionally employed to enable a wide variety of adaptations between whipping and juicing. In other words, the present invention contemplates the utilization of a relatively simple driving unit from which the driving shaft means projects only in one direction. Provision is made to locate the unit bodily in either of a plurality of operative positions with respect to a supporting means which rigidly holds the unit in either position. Accordingly, therefore, I am enabled to employ a driving unit of relatively simplified construction employing a novel degree of compactness, lightness, and portability.

It will be further apparent that the present invention provides an improved interassembly of housing and supporting bracket parts contributing to a novel rigidity and permanence of the driving unit structure and providing a convenient manual handle by which the drive motor unit may be manipulated when removed from the supporting means. Thus, the present device is adaptable to operation for stirring and agitating while manually held in a manner obviously impractical with less portable devices. It should be further noted that the present invention provides a simplified driving construction involving a motor arranged on a vertical axis and supplied with a predetermined air draft applied directly and positively through the portions of the motor requiring cooling.

The present invention further provides an improved simplified oil seal construction adapted to retain oil and lubricant within the gear chamber. It will be appreciated that in the operation of the present device it is important to effectively prevent passage of this lubricant beyond its housing and into the mixing or whipping zone. To this end, attention is particularly directed to the sealing construction shown in Figure 7, wherein the projecting sleeves 80 of the transmission housing 74 which embrace the shafts 18 are annularly recessed at their lower end to receive an annular felt washer 200. While the felt washer thus retained is effective to resist leakage of oil, I have found that the felt may sometimes become soaked. Accordingly, therefore, attention is directed to the fact that the oil sealing collars 82 cooperate to trap the oil within an area or cavity between the collars or cups and the adjacent outer surfaces of the sleeves 80 and to this end each of the collars or cups 82 is provided with a downwardly projecting cylindrical portion 202 embracing and rigid with the associated shaft 18. Accordingly, therefore, the portion 202 makes a tight sealing fit upon the shaft 75

18. A radial wall of the cup 204 extends outwardly from the lower cylindrical portion 202 and terminates in a vertical cylindrical cup portion 206 about the outer walls of the bushing. 5 It is particularly important to note that the cylindrical walls of the cup are spaced a substantial distance from the bushing providing an appreciable cavity which prevents the oil from "creeping" and thus effectively retains any excess lubricant within the cup.

Obviously the foregoing construction provides an appliance capable of being rapidly and efficiently assembled by a few simple assembly operations in quantity production.

15 Obviously the invention is not limited to the specific structural arrangement disclosed herein, but is capable of other modifications and changes without departing from the spirit and scope of the present invention.

Having thus described my invention, what I claim as new and desire to secure by Letters Patent is:

20 1. In a mixing and agitating appliance, a driving unit comprising a motor, a pair of opposed shells embracing the motor, a clamping band operatively engaging said shells for holding the shells in operative position about the motor, and opposed brackets interengaged with said shells and holding extremities of said clamping band in operatively tensioned position about the shells. 25 2. In a mixing and agitating appliance, a driving unit comprising a motor, a pair of opposed shells embracing the motor, a clamping band operatively engaging said shells for holding the shells in operative position about the motor, and opposed brackets interengaged with said shells and holding extremities of said clamping band in operatively tensioned position about the shells, said brackets comprising spaced lug portions receivable within said shells. 30 3. In a mixing and agitating appliance, a driving unit comprising a motor, a pair of opposed shells embracing the motor, a clamping band operatively engaging said shells for holding the shells in operative position about the motor, and opposed brackets interengaged with said shells and holding extremities of said clamping band in operatively tensioned position about the shells. 35 4. In a mixing and agitating appliance, a driving unit comprising a motor, a pair of opposed shells embracing the motor, a clamping band operatively engaging said shells for holding the shells in operative position about the motor, and opposed brackets interengaged with said shells and holding extremities of said clamping band in operatively tensioned position about the shells, said brackets comprising spaced lug portions receivable within said shells, and clamping means acting between said opposed brackets for tensioning said brackets against extremities of said clamping band. 40

45 5. In a mixing and agitating appliance, comprising a driving unit having a housing, a pair of brackets projecting from said housing, each bracket having substantially spaced lugs receivable within complementary apertures in said housing and extending along the inner walls of said housing, a clamping band about said housing having extremities adapted to be urged together to clampingly grip the housing, said extremities being disposed intermediate of said bracket means, and tensioning means extending between 50 said extremities adapted to be urged together to grip the extremities of the clamping band therebetween.

55 6. In a mixing and agitating appliance, comprising a driving unit having a housing, a pair of brackets projecting from said housing, each bracket having substantially spaced lugs receivable within complementary apertures in said housing and extending along the inner walls of said housing, a clamping band about said housing having extremities adapted to be urged together to grip the extremities of the clamping band therebetween.

60 7. In a mixing and agitating appliance, comprising a driving unit having a housing, a pair of brackets projecting from said housing, each bracket having substantially spaced lugs receivable within complementary apertures in said housing and extending along the inner walls of said housing, a clamping band about said housing having extremities adapted to be urged together to

gether to clampingly grip the housing, said extremities being disposed intermediate of said bracket means, and tensioning means extending between said brackets for urging said brackets together to grip the extremities of the clamping band therebetween, and a manually engageable handle rigid with said bracket at a point radially remote from said housing and having a spaced portion rigidly connected with said housing adjacent an extremity thereof and providing a truss bracket construction for supporting said housing.

6. In a mixer and juicer, a driving unit comprising a driving motor, an axially extending housing for said motor having a driving member projecting therefrom at one axial extremity for operative association with an agitating member, bracket means extending outwardly from the side of said housing and comprising means for coupling with a column of a supporting base member, and means adjacent the other axial extremity of said housing for interfitting engagement with a lower portion of said supporting base member.

7. In a mixer and juicer, in combination with a supporting base construction comprising an upwardly projecting pedestal, a driving unit adapted to rotate an agitator or the like comprising a driving motor, a housing for said motor, bracket means extending outwardly from a side wall of said housing and coupled with said pedestal, and a complementarily interengageable means comprising a member associated with an extremity of said housing and a complementary means on said supporting base at a point remote from said pedestal operative to interassociate the housing and base for locating the housing relatively fixedly in the plane of said base against displacement in all horizontal directions.

8. In a mixer and juicer, comprising in combination supporting means having a generally horizontal base and an upstanding pedestal, a driving unit adapted for rotating an agitator or the like comprising a drive motor having a housing, bracket means projecting outwardly from the side wall of said housing, means adjacent an extremity of said housing and interengageable with a complementary means located on said base at a point removed from the pedestal for fixedly locating the housing against movement in all directions in the plane of said base, and releasable means associated with said bracket for coupling said bracket with said pedestal.

9. In a mixer and juicer, comprising in combination supporting means having a generally horizontal base and an upstanding pedestal, a driving unit adapted for rotating an agitator or the like comprising a drive motor having a housing, bracket means projecting outwardly from the side wall of said housing, means adjacent an extremity of said housing and interengageable with a complementary means located on said base at a point removed from the pedestal for fixedly locating the housing in the plane of said base, and releasable means associated with said bracket for coupling said bracket with said pedestal, said last named means being constructed and arranged to resist relative movement of said driving unit vertically and angularly with respect to said complementary means.

10. In a mixer and juicer, comprising in combination supporting means having a generally

horizontal base and an upstanding pedestal, a driving unit adapted for rotating an agitator or the like comprising a drive motor having a housing, bracket means projecting outwardly from the side wall of said housing, means adjacent an extremity of said housing and interengageable with a complementary means located on said base at a point removed from the pedestal for fixedly locating the housing in the plane of said base, and releasable means associated with said bracket for coupling said bracket with said pedestal, said last named means being constructed and arranged to resist relative movement of said driving unit vertically and angularly with respect to said complementary means, and comprising a clip releasably engageable with said pedestal and said bracket.

11. In a mixing device of the class described, comprising a driving unit adapted for driving an agitator or the like, and a supporting member for the driving unit, means pivotally associating said driving unit with the supporting member, and abutment stop means for adjustably determining one rotational position of said driving unit about the pivot, said last named means comprising an abutment stop member shiftable in a predetermined path and a manually adjustable member shiftable laterally with respect thereto and manually actuatable to locate said abutment member in said path.

12. In a mixing device of the class described, comprising a driving unit adapted for driving an agitator or the like, and a supporting member for the driving unit, means pivotally associating said driving unit with the supporting member, and abutment stop means for adjustably determining one rotational position of said driving unit about the pivot, said last named means including an abutment member mounted on said base for movement in a predetermined longitudinal path, a cam surface operatively associated with said abutment member and a manually adjustable member threadedly engaged with said pedestal for adjustable movement laterally with respect to said abutment member comprising means engageable with said cam surface to determine the shifted position of said abutment member in accordance with the lateral position of said manual adjustment means.

13. A mixing appliance of the class described comprising a supporting base, an upstanding pedestal on the base and a driving unit mounted on the pedestal, said driving unit including a transmission housing having an outwardly projecting bushing, an agitator shaft extending through said bushing, and means to prevent loss of lubricant along said shaft comprising an annular resilient shaft embracing collar disposed within a recess in an extremity of said bushing and gripping said shaft to resist passage of lubricant, and a cap member, said cap member having a radially extending wall adjacent said extremity of said bushing and rigidly sealingly joined to said shaft for rotation therewith, said radially extending wall terminating outwardly in a cylindrical wall portion projecting axially adjacent the outer surface of said bushing, said last named wall portion being spaced substantially from said surface to provide an appreciable recess adapted to resist creeping of lubricant.

JAMES J. GOUGH.
